His

UNITED STATES PATENT OFFICE.

FRED M. LOCKE, OF VICTOR, NEW YORK.

INSULATOR.

Application filed August 9, 1920. Serial No. 402,277.

The present invention relates to insulators and more particularly to the type known as suspension insulators in which one or more insulating members are suspended from above and have the conductor suspended therefrom, an object of this invention being to provide an insulator which will have an insulating member free from the strains or stresses of suspension so that it will be subject only to electrical stresses or strains.

Another object of the invention is to provide for connecting the terminals such as the strain pin and the suspending means so that a maximum electrical distance between these terminals is obtained. A still further object of the invention is to connect the terminals to an insulating member in such a manner that said member is placed under compression by the strain on the insulator and not under tension. Another and further object of the invention is to provide an insulator element formed of two insulating members, one of which carries the mechanical strain while the other carries the greatest electrical strain and is substantially free from mechanical strain so that the electrical strain is more evenly distributed over the surface of the insulator than has heretofore been possible, causing less corona effect. A still further object is to provide an insulator which is not subject to a high electrical flashover but will spill over at about its wet flashover voltage.

To these and other ends the invention consists of certain parts and combinations of parts, all of which will be hereinafter described, the novel features being pointed out in the appended claims.

In the drawings:

Fig. 1 is a plan view of a suspension insulator element constructed in accordance with this invention;

Fig. 2 is a vertical section through the insulator illustrated in Fig. 1;

Fig. 3 shows two of the insulators connected and in side elevation;

Fig. 4 is a fragmentary sectional view showing another embodiment of the connection between the suspending means and the lower insulator member; and

Fig. 5 is a fragmentary view of the under side of the insulator illustrated in Fig. 4.

According to the illustrated embodiment of the invention each insulator element comprises an insulating member 1 with means for suspending the same in such a manner

that the insulating member is substantially free of all the strains and stresses of suspension. This suspending means in this instance, embodies an insulating member 2 on which the member 1 rests and a suspending device 3, in this instance, formed from a single strand of wire or other suitable material which is laced through openings 4 in the insulating member 2 adjacent the periphery of the latter and beyond the periphery of the insulating member 1, the strand also being connected with a suitable support such as an eye 5 formed in the lower end of a hanger arranged above it or in the lower end of a strain pin 6 which is connected to the insulating member 2 of the insulating element next above in any suitable manner as that hereinafter described.

The insulating member 2 may be of substantially convex or cup shaped form and the insulating member 1 preferably conforms to the upper face of the member 2. The strand or suspended device 3 preferably engages the insulating member 1 at its periphery as at 7 and may also engage said insulating member 1 at 8 at the periphery of the upstanding hollow boss 9 on said member 1. This arrangement holds the insulating member 1 centered on the member 2. If desired, the space between the members 1 and 2 may be filled with an insulating or other compound which will reduce the static discharge between them. An asphalt compound of high melting point may be employed in this connection. Instead of using a single strand or cable 3 there may be employed a number of rods 3^a anchored at their upper ends in any suitable manner and having their lower ends passed through eyes 3^b in anchoring pins 3^c which are passed through the openings 4^a and secured by washers 3^d at their lower ends as shown in Figs. 4 and 5. In both illustrated forms of the invention the insulating member 2 may have an annular skirt or flange 10 depending therefrom within the openings 4 so as to increase the insulating surface and arcing distance between the terminals of the insulator formed by the suspending device and the center strain pin.

The strain pin 6 may be secured to the insulator in any suitable manner. It is preferred however to provide a loose connection between the pin and the insulator and to this end the insulating member 2 is provided with a central upstanding pocketed

boss 11 on its upper side and a central opening 12 extending from the pocket of the boss to the under side of the insulator, this opening preferably flaring toward its lower end. 5 Within the pocket of the boss 11 a seat 13 may be arranged in the form of a ring or annulus and cooperating with this seat is a removable ball shaped bearing 14, in this instance, having screw threaded connection 10 with the upper end of the strain pin 6, the latter extending through the opening 12. This connection of the strain pin with the insulating member 2 permits the lateral swinging 15 of the strain pin so that any lateral strain on the insulator relatively to the pin will equalize the strain on the insulator and not tend to crack such insulator.

From the foregoing it will be seen that there has been provided a suspension insulator having an insulating member which is substantially free from the strains and stresses of suspension and takes the principal electrical strain of the insulator. This suspending means preferably embodies another 25 insulating member which takes substantially all of the mechanical strains and stresses of suspension. The mechanical strain on this second mentioned insulating member is in the form of compression and this is obtained 30 by making said insulating member of substantially cup form and connecting the two terminals, one at the center of the member and the other at the periphery of the member. Another advantage of connecting the 35 terminals, one at the center and the other at the periphery of an insulating member is that it is possible to increase the thickness of the insulating member so as to secure a greater distance between the terminals of the 40 insulator than when the terminals are both connected substantially at the center. An insulator constructed in accordance with this invention distributes the electrical strain over the surface of the insulator, so that it 45 is not concentrated at the center.

What I claim as my invention and desire to secure by Letters Patent is:

1. A suspension insulator comprising a lower insulating member having a central opening and flaring outwardly and downwardly with reference to its center, its lower edge being below the central portion through which the opening is provided, a strain pin extending through said central opening, a suspending means connected to said lower insulating member adjacent the edge of the latter and at a point below the central portion through which the opening is provided, so that there is imposed on the lower insulating member compression strains from the suspending means to the strain pin in a direction which is inward and upward, and a second insulating member loosely supported on the lower insulating member, covering the upper end of the strain pin and the opening therethrough and extending downwardly and outwardly over the upper face of the lower insulating member. 65

2. A suspension insulator comprising a lower insulating member having a central opening and flaring outwardly and downwardly with reference to its center, its lower edge being below the central portion through which the opening is provided, a strain pin extending through said central opening, suspending means connected to said lower insulating member adjacent the edge of the latter and at a point below said central portion through which the opening is provided so that compression strains are imposed on the lower insulating member extending between the suspending means and the strain pin through the flaring portion of the insulator, and a second insulating member having a portion flaring outwardly and downwardly 85 from its central portion covering the upper end of the strain pin and extending downwardly over the upper face of the lower insulating member to a point adjacent the suspending means, so that it is entirely free 90 from all mechanical strains, at the same time, insulating the electrical strains between the strain pin and the suspending means.

FRED M. LOCKE.

CERTIFICATE OF CORRECTION.

Patent No. 1,608,026, granted November 23, 1926.

to FRED M. LOCKE.

It is hereby certified that error appears in the printed specification of the above mentioned patent requiring correction as follows: Page 2, after line 45, insert "The insulator is not subjected to both mechanical and electrical stresses at one central point and a heavy lightning discharge will spill over the outer part of the insulator rather than to put heavy strains through the insulator"; and that the said Letters Patent should be read with this correction therein that the same may conform to the record of the case in the Patent Office.

Signed and sealed this 15th day of February, A. D. 1927.

Seal.

William A. Kinnan,
Acting Commissioner of Patents.
